(57) **CLAIM**

The ornamental design for a catheter insertion device, as shown and described.

DESCRIPTION

FIG. 1 is an upper perspective view of a first embodiment of a catheter insertion device.

FIG. 2 is a lower perspective view of the catheter insertion device of FIG. 1.

FIG. 3 is a bottom view of the catheter insertion device of FIG. 1.

FIG. 4 is a left side view of the catheter insertion device of FIG. 1, of which the right side view is a mirror image.

FIG. 5 is a top view of the catheter insertion device of FIG. 1.

FIG. 6 is a front end view of the catheter insertion device of FIG. 1, of which the rear end view is a mirror image.

FIG. 7 is an upper perspective view of a second embodiment of a catheter insertion device.

FIG. 8 is a lower perspective view of the catheter insertion device of FIG. 7.

FIG. 9 is a bottom view of the catheter insertion device of FIG. 7.

FIG. 10 is a left side view of the catheter insertion device of FIG. 7, of which the right side view is a mirror image.

FIG. 11 is a top view of the catheter insertion device of FIG. 7.

FIG. 12 is a front end view of the catheter insertion device of FIG. 7, of which the rear end view is a mirror image.

FIG. 13 is an upper perspective view of a third embodiment of a catheter insertion device.

FIG. 14 is a lower perspective view of the catheter insertion device of FIG. 13.

FIG. 15 is a bottom view of the catheter insertion device of FIG. 13.

FIG. 16 is a left side view of the catheter insertion device of FIG. 13, of which the right side view is a mirror image.

FIG. 17 is a top view of the catheter insertion device of FIG. 13; and,

FIG. 18 is a front end view of the catheter insertion device of FIG. 13, of which the rear end view is a mirror image.

The broken lines in the drawings illustrate portions of the catheter insertion device which form no part of the claimed design.
